D6-582

EX

OR D 15,786

15,786.

Patented Feb. 10, 1885.

UNITED STATES PATENT OFFICE.

WILLIAM GILMOUR, OF PHILADELPHIA, PENNSYLVANIA, ASSIGNOR TO
GEORGE W. ENNIS & CO., OF SAME PLACE.

DESIGN FOR A RUG.

SPECIFICATION forming part of Design No. 15,786, dated February 10, 1885.

Application filed January 7, 1885. Term of patent 3½ years.

To all whom it may concern:

Be it known that I, WILLIAM GILMOUR, a citizen of the United States, residing at Philadelphia, in the State of Pennsylvania, have 5 invented a new Design for Rugs, of which the following is a specification.

The nature of my invention is fully set forth in the accompanying photographic illustration, forming part hereof, to which reference is made.

10

What I claim as my invention is—
The design for a rug, as shown.

WILLIAM GILMOUR.

Witnesses:

FRANK P. BEAL,
W. H. MERSHON.
